SPARKLER TOY

Perry Feuer, Roslyn, N.Y., assignor to Yuletide Enterprises, Inc., Hicksville, N.Y.

Filed Mar. 30, 1973, Ser. No. 346,287

Term of patent 14 years

Int. Cl. D21—01

U.S. Cl. D34—15 M

FIG. 1 is a front elevational view of a sparkler toy showing my new design;

FIG. 2 is a right side elevational view thereof;

FIG. 3 is a rear elevational view thereof;

FIG. 4 is a left side elevational view thereof;

FIG. 5 is a top plan view thereof; and,

FIG. 6 is a bottom plan view thereof.

I claim:

The ornamental design for a sparkler toy, as shown.
